(No Model.)

H. KAUTZ.

CIGAR BUNDLING MACHINE.

No. 364,257.

Patented June 7, 1887.

N. PETERS, Photo-Lithographer, Washington, D. C.

UNITED STATES PATENT OFFICE.

HENRY KAUTZ, OF LITIZ, PENNSYLVANIA, ASSIGNOR OF ONE-HALF TO
JAMES K. GREIDER, OF SAME PLACE.

CIGAR-BUNDLING MACHINE.

SPECIFICATION forming part of Letters Patent No. 364,257, dated June 7, 1887.

Application filed February 11, 1887. Serial No. 227,307. (No model.)

To all whom it may concern:

Be it known that I, HENRY KAUTZ, a citizen of the United States, residing at Litiz, in the county of Lancaster and State of Pennsylvania, have invented new and useful Improvements in Cigar-Bundling Machines, of which the following is a specification.

The invention relates to improvements in machines for pressing cigars, in order to tie the same into bundles, the object being to make such a machine of simple construction, and one in which the necessary vertical and horizontal pressure will be produced simultaneously.

15 The invention consists in the construction and novel arrangement of parts, hereinafter described, pointed out in the claims, and illustrated in the accompanying drawings, in which—

20 Figure 1 represents a perspective view of the invention. Fig. 2 represents a rear or back view of the same. Fig. 3 represents a perspective view of the follower, showing it extended in dotted lines and contracted in 25 full lines to press small bundles. Fig. 4 represents a longitudinal sectional view. Fig. 5 represents a plan view of the square cam-block.

Referring to the drawings by letter, A designates the frame of the machine, of general rectangular form and with its front side open, or not provided with a wall. a is one end wall of the said frame, having secured to it a standard, a', the upper end of which is bifurcated, 30 and has pivoted between its arms the end of a lever, B, upon which is pivoted a depending rod, b, the arms of the bifurcated upper end of which lie on each side of the lever.

b' is a pressure foot or disk on the lower end 40 of the rod b. The said rod hangs about midway between the end wall of the frame and the movable partition or wall C, the inner edge of which is provided with threaded recesses to engage the set-screws c, which pass through 45 the longitudinal slots c' in the rear wall of the frame and have washers between said slots and their heads, as shown in the drawings.

D is a longitudinal shaft having its inner end furnished with a disk-like head, d, which 50 rotates in a chamber formed by the wall or

partition C, and the collar d', having its interior hollow to form said chamber, and with the neck d" of the shaft turning in its central opening to the outer side of the chamber. The outer end of the shaft D turns in a bearing 55 formed in the end of the main frame, opposite the wall a, and upon said shaft, at its center part, is the squared portion E, which passes through a correspondingly-shaped longitudinal opening, e, in a cylindrical block, F, which block has upon it a cam-thread, f, that engages in an inclined groove, g, in a block secured to the floor of the main frame.

h is a circumferential shoulder at the inner end of the squared portion E of the shaft D, 65 and H is a laterally-extending arm secured to the shaft, to the inner side of said shoulder, and having connected loosely to a pin, near its end, a link-rod h', the upper slotted end of which passes over the end of the lever B, and 70 is pivoted thereto, as shown, and rendered adjustable thereon by means of the opening shown in the drawings, in any of which openings the pivotal pin will fit.

The lever B and the rod b are also rendered 75 mutually adjustable on each other by means of adjusting-holes in each and a pivotal pin that will fit into corresponding holes of each series, as shown. Both the end wall, a, and the partition C have the clips i attached to their lower 80 inner edges. The said clips are triangular in cross-section, as shown, to better support the cigars set upon them.

I is a handle secured to the upper surface of the cylindrical cam-block F, and by means of 85 which the latter is rotated back and forth, the rear wall of the machine, on the adjacent side of the movable partition C, being cut down to allow of its being turned far enough back.

J is the follower, composed of the rectangular block j, having the clip j', triangular in cross-section, secured to its outer edge, and of the sheet-metal engaging-plate j", having its ends j" bent around the ends of the block j in such manner as to be adjustable inward and 95 outward thereon. The said plate has secured to its under surface a clip, j', in all respects similar but opposite to the clip j". The said two clips are also similar to the clips i.

By pulling out or pushing in the plate j" the 100

follower can be extended or contracted. When so extended, a piece, K, having a similar longitudinal section to that of the block j, is engaged upon the plate j², and pins k k, standing from its inner edge, engage in openings in the meeting edge of the block j, so as to bind the piece K and said block together. The follower is thus adjusted to different distances between the wall a and the partition C, which themselves are adjusted to press larger or smaller bundles of cigars.

In pressing the bundles the wall and partition are set apart a distance of about one-quarter of an inch greater than the width of the box in which the cigars are to be packed. The ribbon is then laid upon the floor of the frame and its ends brought up to the top of the end wall, a, and the partition C, respectively. The handle I is then turned forward, bringing down the arm E, which, by means of the link-rod h', lever B, rod b, and presser-disk b', depresses the follower J, which has been placed below said disk and above the cigars, so that the latter are compressed vertically thereby. The horizontal pressure of the cigars is accomplished by means of the movable partition C, which is driven against them by the inner end of the cylindrical cam-block impinging against the shoulder h of the shaft D. When the said partition is moved sufficiently toward the end wall, a, it is held in position by the set-screws e, the follower removed, and the ribbon tied, completing the bundle. When the necessary number of bundles are made, they are packed in the box in the usual manner.

Having described my invention, I claim—

1. In a machine for pressing cigars in bundles, the combination of the main frame, the movable partition, the shaft having one end journaled in the movable partition and the other end arranged to slide in a bearing in the proper end wall of the main frame and provided with a squared portion and circumferential shoulder between said end wall and the partition, the cam-block provided with the inclined cam-groove and secured to the floor of the frame, and the cylindrical block provided with the cam-thread to engage said cam-groove and with a central longitudinal opening to slide on the squared part of the shaft and the lever, whereby the cylindrical block

is rotated, and, sliding on the shaft, impinges against the shoulder thereon and moves the partition toward the proper end wall, so as to compress the cigars between said wall and itself, substantially as specified.

2. In a machine to compress cigars in bundles, the combination of the main frame, the lever having its outer end pivoted to the frame, the rod pivoted to and depending from said lever, the presser-foot on the lower end of said rod, the follower constructed to be extended and contracted, and mechanism, substantially as described, whereby said lever may be depressed to bring the follower to bear on the cigars, substantially as specified.

3. In a machine to compress cigars in bundles, the combination, with the main frame, the pivoted lever-rod extending therefrom, presser-foot, and follower, all constructed substantially as described, of the shaft having the squared portion and journaled in the main frame and also in a partition, C, the cylindrical block on the squared part of said shaft, the handle secured to said block, and the link-rod connecting said shaft with the outer end of the pivoted lever, so that the latter will be depressed by rotating the cylindrical block and shaft by means of the handle and will press the follower vertically downward upon the cigars, substantially as specified.

4. The combination of the main frame A, having the end wall or bearing, a, the movable partition C, the lever B, the presser-foot, and follower constructed substantially as specified, the shaft having the squared portion and circumferential shoulder, the cylindrical block on said shaft, provided with the cam-thread, the block secured to the main frame and provided with a cam-groove engaging said thread, and the link-rod connecting the shaft with the end of the pivoted lever, all constructed and arranged substantially as and for the purpose specified.

In testimony that I claim the foregoing as my own I have hereto affixed my signature in presence of two witnesses.

HENRY KAUTZ.
